AUTOMOBILE

Clifford C. Voss, Clawson, Mich., assignor to Chrysler Corporation, Highland Park, Mich., a corporation of Delaware

Application June 11, 1956, Serial No. 41,829

Term of patent 14 years

(Cl. D14—3)

Fig. 1 is a side elevational view of an automobile, showing my new design with the side opposite being similar to the one illustrated;

Fig. 2 is a front elevational view thereof;

Fig. 3 is a perspective view thereof; and

Fig. 4 is a perspective view from a position above the automobile.

The dominant features of my design reside in the portions shown by means of full lines in the drawing.

I claim:

The ornamental design for an automobile, substantially as shown and described.
